UNITED STATES PATENT OFFICE.

JOHN A. CHRISTMANN, OF MOUNT PULASKI, ILLINOIS.

DESIGN FOR A PICTURE-HANGER.

SPECIFICATION forming part of Design No. 34,820, dated July 23, 1901.

Application filed April 25, 1901. Serial No. 57,504. Term of patent 14 years.

To all whom it may concern:

Be it known that I, JOHN A. CHRISTMANN, a citizen of the United States, and a resident of Mount Pulaski, in the county of Logan and State of Illinois, have invented and produced 5 a new and original Design for a Picture-Hanger, of which the following is a full, clear, and exact description.

Reference is to be had to the accompanying drawings, forming a part of this specification, in which similar characters of reference indicate corresponding parts in both the figures.

Figure 1 is a front elevation of a picture-hanger, showing my design; and Fig. 2 is a 5 transverse section of the same on the line 2 2 in Fig. 1.

The design consists of a straight and flat plate A, from the front face of which project

buttons B, located one below the other and spaced apart, a projecting loop C appearing 20 lengthwise of and at the longitudinal center of the front face of the plate next to the last button, and the ends of the plate appearing with transverse openings D.

Having thus fully described my invention, 25 I claim as new and desire to secure by Letters Patent—

The design for a picture-hanger as herein shown and described.

In testimony whereof I have signed my 30 name to this specification in the presence of two subscribing witnesses.

JOHN A. CHRISTMANN.

Witnesses:

L. F. WEIDENBACKER,
W. J. HAGEL.
